UNITED STATES PATENT OFFICE.

ALBERT EDWARD JONES, OF FIUME, AUSTRIA-HUNGARY, ASSIGNOR TO WHITEHEAD & CO., OF FIUME, AUSTRIA-HUNGARY.

MEANS FOR LAUNCHING TORPEDOES FROM THE SIDES OF SHIPS.

1,046,192.

Specification of Letters Patent.

Patented Dec. 3, 1912.

Application filed March 12, 1912. Serial No. 683,187.

To all whom it may concern:

Be it known that I, ALBERT EDWARD JONES, a subject of the King of Great Britain, and resident of Via Volosca No. 2, 5 Fiume, Austria-Hungary, have invented new and useful Improvements in and Relating to Means for Launching Torpedoes from the Sides of Ships, of which the following is a full and complete description.

10 This invention has for its object means for launching torpedoes from the sides of a submarine vessel, a torpedo boat or other light vessel at any angle and by means of a torpedo launching frame jointed to the sides 15 of the ship.

The invention has for its object to insure that the torpedo shall exactly follow the direction imparted by the torpedo launching frame at the moment at which the latter is 20 locked and to prevent any deviation due to the gyroscope becoming operative prematurely.

Means are known for launching torpedoes from the sides of a vessel at any angle and 25 by means of torpedo-carrying frames jointed to the sides of the ship but in these devices the starting mechanism and the release of the torpedo are generally controlled by the turning movement of the frame itself 30 so that the starting of the wheel of the gyroscope and the release of the gyroscope are effected during this turning movement, that is to say, before the framework has been locked. As the torpedo obeys the gyroscope 35 it will be understood that in these conditions it will not follow the trajectory indicated by the locked position of the frame but will always be brought back by the gyroscope into a direction which corresponds with that occupied by the frame at 40 the moment at which (during the turning of the latter) the gyroscope was released.

In order that the gyroscope may fulfil the functions that have been assigned to it with 45 precision it is necessary on the one hand that it should not be released before the frame has been locked but that on the other hand this release should take place before the torpedo has been released from the frame 50 which serves as its guide.

The invention furnishes a solution of this problem and consists in mechanically connecting the rocking torpedo frame with the mechanism for starting and launching the 55 torpedo, in such a manner that this mecha-

nism cannot be rendered operative until after the frame has been locked in the firing position, while at the same time the mechanism comprises a retarding device which allows the gyroscope time to become released before the torpedo is left to itself, so that the torpedo is always brought back into the proper direction. The mechanical devices by means of which this problem is solved are illustrated in the accompanying drawing, in which:—

Figure 1 is a side elevation of the device. Fig. 2 is a plan thereof. Fig. 3 is a partial side elevation of the mechanism for releasing the torpedo. Fig. 4 is a detail to a larger scale of a portion of Fig. 3. Figs. 5 and 6 are respectively an end elevation and a side elevation of the shutters for retaining the torpedo. Fig. 7 is a detail plan view of the means for operating the shields. 75 Figs. 8 and 9 are detail sectional views of the torpedo releasing means.

The frame *a* is hinged at *b* to the side of the vessel along which it can be turned back and it presents the guide shields *c c'* and the flaps or doors *f f'* which release the torpedo at the proper moment. The shield *c* at the front extremity of the frame is connected at *d* by a cable *g* with a winch drum *h* arranged upon the boat and provided with an arm *i* upon the trajectory of which a compressed air valve *j* is arranged. This valve is connected by a pipe *k* with a cylinder *m* inclosing a piston *n*, the rod *o* of which is rigidly connected with the bar *p* movable inside the frame *a* and ending in the operating hook *q* which acts upon the tail *r* of the torpedo; *s* is the fixed bolt serving to act upon the air supply lever *t*; *u* is the usual guide snug of the torpedo and *v* is a stop pivoted at the front of the bar *p* for releasing the torpedo at the proper moment. In proximity to its middle the cylinder *m* is perforated with water discharge openings 1 of considerable diameter and in proximity of its extremity with other apertures 2 of smaller diameter. The movable bar *p* carries a snug *3* (Fig. 3) movable in a slot 4 formed in the part 5 of the frame *a* and serving to guide the bar *p* (Figs. 2 and 3). 105 The upper retaining flap *f'* (Fig. 5) is pivoted at 6 and is capable of effecting a certain longitudinal movement owing to the provision of the spaces 7 shown in Fig. 6. The upper door *f'* engages with the lower door 110

5 *f* by means of nipples 8 engaged in holes 9 in the lower door in such a manner that when the two doors are thus locked (see Figs. 5 and 6) they form a rigid shield which supports the torpedo against the lateral pressure of the water.

10 Each of the shields *f* and *f'* is provided with a small arm 10 (Fig. 5) connected with a rod 11 which is pivoted to a lever 12 mounted on a vertical pivot 13 (Fig. 5) carrying an arm 14 to which one end of a spring 15 is attached while its other end is attached to the frame *a*. The shield *f'* is movable longitudinally on its fixed shaft. The lever 15 16 is engaged by one extremity 17 in a recess of the shield *f'* (see Fig. 7). The lever 16 is fulcrumed on its center 19 and its other end placed over the groove 4 in the bar 5. The pivot 19 of the lever 16 is placed over 20 a lateral extension 21 of the bar 5. When the bar *p* is pushed forward, the projection 3 of this bar, which is displaced in the groove 4, strikes one end 20 of the lever 16 and swings it around its pivot 19, thus producing a longitudinal displacement of the shield *f'*, which is released from the lower shield *f*. When the shields *f* and *f'* are disengaged from each other, these shields are 25 opened to allow the torpedo to escape laterally, by means of the spring 15 acting through the lever 14, the vertical pivot 13 and the two levers 12, on the two bars 11, which are connected to the arms 10 and 10 integral with the shields *f* and *f'* respectively.

30 The operation is as follows:—The position of the arm *i* upon the drum *h* is regulated in such a manner that at the moment at which the frame reaches its firing position 40 (which is not necessarily perpendicular to the ship's side as shown in the drawing) the cable *g* applies the arm *i* against the air supply valve *j* in order to admit compressed air into the cylinder *m* through the pipe *h*. 45 The piston *n* is then pressed forward with a velocity which depends simultaneously on the air pressure and upon the size of the apertures 1 for discharging the water. By the intermediary of the bar *p* and of the 50 hook *q* it causes the torpedo to advance sufficiently to produce the rocking of the air supply lever *t* in contact with the bolt *s*. The motor of the torpedo is started and the wheel of the gyroscope is started but without the gyroscope yet being released. In 55 proportion as the piston *n* covers the orifices 1 its speed is reduced because the escape of the water is throttled at 1; the piston continues its stroke with the reduced speed which is caused by the discharge of the water through the smaller aperture 2. This causes a retardation in the advance of the torpedo and consequently retardation in its departure and this retardation (which 60 forms the special feature of this invention)

affords time for the wheel of the gyroscope to become completely operative and the time necessary for the gyroscope as a whole to become released by the turning of the frame before the torpedo is released from the 70 frame.

75 When the piston *n* has nearly reached the end of its stroke the small lever *v* which forms a stop for the snug *u* and an obstacle to the advance of the torpedo is lifted. The lever *v*, which has substantially the shape of a bell crank lever is pivoted at the front end of the movable bar *p*. See Figs. 8 and 9. The width of the lever *v* is slightly greater than the width of the groove 4 of the stationary bar 5. When the lever *v* is in the position shown in Fig. 8 it is supposed that the propellers of the torpedo are in motion. The projection *u* of the torpedo is pressed against the lever *v*. But this lever cannot 80 be lifted. Consequently it holds back the torpedo, which cannot advance quicker than the bar *p* advances. As shown in Fig. 9, the lever *v* has reached the end of the bar 5, and it is free to be lifted by the pressure of 85 the projection *u* of the torpedo, and as soon as it is lifted, the torpedo is free to start with the speed given by these propellers. Simultaneously the snug 3 on the bar *p* rocks the lever 16 which serves to displace 90 the upper shield *f'* longitudinally and thereby to disengage the two shields which are then able to separate so as to release the torpedo because the traction spring 15 acts by the intermediary of the arm 14 of the pivot 100 13 the levers 12 and of the connecting rods 11 upon the small arms 10 of the shields. The torpedo is then able to start freely.

95 The main advantages of the device are as follows: (1) In view of the fact that the starting mechanism for the torpedo, the launching and the release of the gyroscope do not take place until after the locking of the frame *a* it becomes certain that the gyroscope will have no tendency to cause the 105 torpedo to follow a different trajectory from that imparted by the direction of the frame after it has been locked. (2) In view of the fact that the retarding device affords time for the gyroscope to become released before the torpedo is left to itself that is to say while it is still guided in the firing direction by the frame *a*, the certainty is obtained that the gyroscope will always return the 110 torpedo to this desired direction even if this 120 torpedo should be overturned or deviated during its fall into the water.

Having now particularly described and ascertained the nature of my invention and in what manner the same is to be performed, 125 I declare that what I claim is:

1. In a device of the character described, a frame for supporting a torpedo, said torpedo being formed with a projecting guiding extension, an ejecting member for eject- 130

- ing said torpedo from said frame, means 1
extending from said ejecting member into 5
engagement with said frame for guiding the
torpedo and the ejecting member until the
5 torpedo is free of the frame, and means for
positively holding said torpedo in slidable
engagement with the frame until said eject-
ing member has moved to substantially its
outermost position.
- 10 2. In a device of the character described,
a framework for supporting a torpedo, a pin
projecting from said framework into the
path of movement of the torpedo for setting
in motion the means for rotating the pro-
15 pellers of the torpedo, means for positively
holding the torpedo in said framework for
a predetermined time after the power has
been turned on to the propellers of the tor-
pedo, an ejecting member for moving said
20 torpedo longitudinally of said framework,
and means for releasing said torpedo from
said framework after said ejecting member
has reached its extreme outer position.
- 25 3. In a device of the character described,
a frame for supporting a torpedo, an eject-
ing member for ejecting said torpedo from
said frame, a piston rod connected with said
ejecting member, a piston connected with
30 said piston rod, a cylinder surrounding said
piston formed with comparatively large ap-
ertures midway the length thereof and com-
paratively small apertures at one end, and
means acting on the rear of said piston for
35 moving the same, the size of said apertures
permitting the water in said cylinder to es-
cape rapidly from the first movement of the
piston and more slowly upon a continued
movement of the piston whereby the move-
ment of the ejecting member is retarded.
4. In a device of the character described, 40
a torpedo supporting frame having movable
and spring actuated shields, a cylinder, a
fluid operated piston in the cylinder, and
means operated from the piston for releas-
ing the shields to permit them to open just 45
before the piston has reached the end of its
stroke.
5. In a device of the character described,
a torpedo supporting frame having pivoted
and spring actuated shields, the shields hav-
ing interlocking engagement with each 50
other and one of them slidable on its pivot, a
pivoted lever having an end engaging the
slidably mounted shield, a reciprocating bar
having a lug for engaging the other end of 55
the said lever, and means for operating said
bar.
6. In a device of the character described,
a supporting frame having movable shields,
a torpedo in the frame and having a projec-
tion, a reciprocating bar, means for releas-
ing the shields by said bar, and a locking 60
lever on the end of the reciprocating bar and
adapted to be operated by the projection of
the torpedo. 65
7. In a device of the character described,
a frame having movable shields, a torpedo
in the frame and having a projection, a cyl-
inder, a fluid operated piston in the cylin-
der, a sliding bar rigidly secured to the pis-
ton, means for releasing the shields from 70
said bar, and a locking lever on the end of
the sliding bar and adapted to be operated
by the projection on the torpedo. 75
